(57) **CLAIM**

The ornamental design for a mobile phone, as shown and described.

DESCRIPTION

1. Mobile phone

1.1 : Perspective

1.2 : Front

1.3 : Back

1.4 : Left

1.5 : Right

1.6 : Top

1.7 : Bottom

1.8 : Back perspective view

1.9 : Perspective view 2

1.10 : Front view 2

1.11 : Back view 2

1.12 : Left view 2

1.13 : Right view 2

1.14 : Top view 2

1.15 : Bottom view 2

1.16 : Back perspective view 2

The broken lines depict portions of a mobile phone that form no part of the claimed design; the fine lines on the drawings indicate the flat surface, curved surface or display part; reproductions 1.1 to 1.8 are front perspective, front, back, left, right, top, bottom and back perspective views of the mobile phone in folded state; reproductions 1.9 to 1.16 are front perspective, front, back, left, right, top, bottom and back perspective views in a condition that the claimed design opened completely; this design is for a foldable mobile phone with a flexible OLED.

1 Claim, 16 Drawing Sheets
